UNITED STATES PATENT OFFICE.

EUGÈNE MOREAU, OF PHILADELPHIA, PENNSYLVANIA, ASSIGNOR TO THE SIEMENS LUNGREN COMPANY, OF PENNSYLVANIA.

GAS-BURNER.

SPECIFICATION forming part of Letters Patent No. 389,757, dated September 18, 1888.

Application filed April 2, 1887. Serial No. 233,443. (No model.) Patented in England May 31, 1887. No. 7,885.

To all whom it may concern:

Be it known that I, EUGÈNE MOREAU, a citizen of the Republic of France, residing at Philadelphia, in the county of Philadelphia and State of Pennsylvania, have invented certain new and useful Improvements in Gas-Burners, (for which a patent in Great Britain, No. 7,885, bearing date May 31, 1887, has been obtained;) and I do hereby declare the following to be a full, clear, and exact description of the invention, such as will enable others skilled in the art to which it appertains to make and use the same.

My invention relates to that class of lamps wherein the heat of the products of combustion from the flame is imparted to the air-supply and to the combustible gas for increasing the illuminating-power of the flame; and the nature thereof consists in certain improvements in the construction of burners of such lamps, whereby a better combustion of the gas is obtained, the number of parts of which the burner is composed lessened, and the cleaning of the gas-passages facilitated.

25 In the lamp described in English Patent No. 14,335, of November, 1886, the burner which is screwed into the lower part of the gas-chamber consists of a tube-plate provided with a large number of holes for holding together 30 the gas tubes, a series of tubes, each of which is passed through the holes in the tube-plate, a ring to which the lower ends of the tubes are secured, and a stem supporting a deflecting-button which is screwed into the tube-plate.

35 My present invention is an improvement on the burner described in the said English patent; and its object is to simplify and render more economical the construction of the burner, so that it may be finished after being cast entirely by drilling, turning, and milling machinery adapted to the purpose. According 40 to my present invention, all these parts are constructed of one and the same piece of metal by first turning a casting to the required form, then 45 drilling through the same holes for the passage of gas, and finally cutting or milling air-spaces between the holes or bores. I also combine with the burner a central receptacle or chamber, for the reception of impurities, having a 50 removable bottom.

In the accompanying drawings, in which

corresponding parts are designated by similar letters, Figure 1 represents the burner applied to a regenerative gas-lamp of known construction. Fig. 2 is a vertical section showing the 55 burner detached from the lamp. Fig. 3 is a sectional plan of the burner illustrated in Fig. 2. Fig. 4 is a vertical section illustrating the improvements for preventing the deposit of carbon and facilitating the cleaning of the gas- 60 passages. Fig. 5 is a sectional plan of the burner illustrated in Fig. 4. Fig. 6 illustrates a burner the lower rim of which is provided with a protecting device. Fig. 7 illustrates that part of the burner shown in Fig. 2 which 65 is made in a single piece as it appears before the gas and air passages are drilled or cut therein. Fig. 8 illustrates that part of the burner shown in Fig. 4 which is made in a single piece as it appears before the gas and air 70 passages are drilled or cut therein.

In constructing the burner shown in Figs. 2 and 3, the casting is first turned in such a manner as to assume the form shown by the outer bounding-lines of Fig. 3, when the deflecting-button is removed, the threads upon the periphery and upon the lower part of the rod E being cut in this operation. The requisite holes C—in this instance twenty eight in number—are then drilled, and the requisite 80 number of slots d—in this instance twenty-eight—are afterward milled between the holes or bores C from the annular rim D to the shoulder B, and also above the shoulder B to the top of the cylinder. The button F is then fastened upon the stem, and the burner is completed in two parts instead of the many which have been heretofore required. In the burner illustrated in Figs. 4 and 5, the tube-cylinder, instead of extending above the plate or shoulder B, is provided with an inner annular beveled edge, C², immediately under which is the recess or cup G, constructed in the form of an inverted cone, and provided with a downwardly-projecting tubular stem, E', the bore 95 of which is closed by the button F'. As the tubes C' are cleaned by means of a wire driven through them, which forces the carbon deposits upward, the beveled surface C² prevents the accumulation of the carbon residue, and causes 100 it to fall into the recess G below, from which it may be readily removed by unscrewing or

burner is displaced, removing the button F from the hollow stem 25 and the tube E. The lower annular terminal of the burner 30 D is provided with small grooves H, (best shown in Fig. 5,) which compel the air flow 35 toward the flame to reach the gas at a point very near its exit from the burner, and thereby greatly facilitate its combustion. In Fig. 6 a shield, J, is shown for protecting the lower annular terminal of the burner. This shield is of annular form, and is provided on its outer and inner edges with ring-shaped flanges, which fit about the terminal annulus of the burner and protect it from the oxidizing effect of the hot gases. As the shield is removable, it may be readily replaced when it is worn out. In Fig. 7 that part of the burner 40 which is made of a single piece of metal is illustrated, and is shown bored and the air-passages C milled therein. Having thus described my invention, I claim 45 and desire to secure by Letters Patent—

1. A gas-burner comprising an annular bottom, drilled holes for the passage of gas, spaces between the gas-passages cut or milled

out for the passage of air, and a projecting stem, all formed together of a single piece of metal, and a deflecting button supported thereon, as and for the purpose described.

2. A gas-burner provided with a central receptacle or chamber for the reception of impurities, a removable bottom to the central chamber or receptacle, and a series of gas-passages surrounding the central chamber or receptacle, as and for the purpose described.

3. In a gas-burner, the combination of a central chamber or receptacle communicating with the gas-passages, having its upper end beveled at the entrance of the gas-passages, a tubular extension to the central chamber, a button fastened to said extension, and a series of gas-passages surrounding the tubular extension, as and for the purpose described.

In testimony whereof I have affixed my signature in presence of two witnesses.

EUGÈNE MOREAU.
